ELECTRON BEAM GUN SYSTEMS

George L. Hall, Fredericksburg, Va., assignor to International Telephone and Telegraph Corporation, Nutley, N.J., a corporation of Maryland

Application June 21, 1954, Serial No. 437,999

11 Claims. (Cl. 315—31)

This invention relates to electron beam gun systems and more particularly to curved electron beam electrostatic unipotential lens structures incorporated therein.

The most thoroughly studied electrostatic unipotential lens is the symmetrical three-aperture lens as illustrated by numerous textbooks published treating the subject of electron optics. Representative textbooks are "Introduction to Electron Optics" by V. E. Cosslett and "Electrical Optics and the Electron Microscope" by V. K. Zworykin, G. A. Morton, E. G. Ramberg, J. Hillier, and A. W. Vance. Briefly, this type of lens is a development of a two-cylinder lens system, a third cylinder being introduced between two identical cylinders, which may be longer or shorter in length than the middle cylinder. In its simplest form, the cylinders are reduced to simple apertures. The central element, or aperture, may be at a higher or lower potential than the outer two elements or apertures which are maintained at the same potential. If this common potential is zero (ground) and the central element is connected to the cathode of the electron gun system, then only a single negative voltage need be applied, and the arrangement has come to be known as a univoltage, unipotential, or einzel lens. In its generic sense, the lens system of the present invention refers to the einzel or unipotential lens, but differs therefrom in the physical arrangement of the various electrodes incorporated in the lens system of this invention.

A further configuration of a unipotential lens structure is that of the coaxial-cylinder type wherein the inner cylinder may be physically shorter than the outer cylinder with a difference of potential established therebetween for focusing the electron beam. If the potentials applied to the coaxial cylinders are equal, then we have a region of zero difference of potential, commonly referred to as a drift region, said region finding great application in the present development of high velocity electron discharge devices utilizing several of these drift regions with steadily increasing accelerating potentials established therebetween to provide what is commonly referred to as an electron "jump" type of electron gun system.

When the lens structures of the type hereinabove described are utilized to focus electron beams, the equi-potential configuration of the system theoretically should be entirely symmetrical about the horizontal and vertical mid-plane of the system, and, hence, the lens structure has been referred to as a symmetrical lens wherein the refractive indices on both sides of the central element are identical. Regardless of whether the central element is at a lower or higher potential than the outer electrodes, the total effect is to provide a convergent electron lens. In the past, this simple unipotential or einzel lens has found most application in electron microscopes and the usual type of cathode ray tube where a spot of light is swept horizontally across the face of a viewing screen by a horizontal deflection voltage and vertically by a voltage to be observed to obtain a pictorial representation of the voltage being observed.

In certain applications, such as direction finding, it is

2

desirable to employ a cathode ray tube having a focused annular ring displayed on the face of the cathode ray tube with radial deflections being produced by signals applied to equally spaced deflection plates around the circumference of the hollow annular electron beam. It

is possible with such a system to orient the radial deflections in a manner to correspond to signals received from directional antennas such that the radial deflections will point in the direction of the antenna transmitting the signal. To produce the desired undeflected focused annular ring, an electron gun system was constructed employing a cathode capable of producing a hollow cylindrical annular electron beam and an einzel lens structure considered suitable from a theoretical viewpoint to focus the emitted hollow cylindrical electron beam upon the screen for production of the desired annular display ring. The electron gun system utilizing the usual einzel lens structure, that is a physically symmetrical annular electrode structure in which the inner and outer parts of any one electrode are equally spaced about the mean circumference of the electron beam, was found to produce an annular electron beam whose mean diameter varied as the focusing electrode potential was varied above and below the optimum focusing potential. This variation of means beam diameter and consequently the trace diameter is an annoying feature and for successful operation of an annular beam display tube, the mean beam diameter should be made independent of the focusing potential.

It was discovered that a physically symmetrical annular einzel lens exhibits an inherent static non-symmetrical potential distribution as represented by a ring of saddle points of a diameter different from the mean diameter of the hollow cylindrical annular beam. This static electrical dissymmetry was discovered to be one of the factors that produced the undesired variation of mean beam diameter with changing focusing potential. Further investigation of einzel lens structures, particularly those incorporating a drift region area, indicated a second factor which further complicated the desired focusing of an annular electron beam. This second factor was the effect of the space charge present in the drift region of this type of einzel lens structures. The first factor predominates in lens systems consisting of electrodes of various shapes and various potentials. The second factor, while its effect may be felt in all einzel lens systems, is usually found in those lens structures having drift tube regions.

It is an object of this invention to provide an improved einzel lens structure for focusing hollow curved electron beams whose mean circumference is unaffected by the space charge within the lens elements or variations of focusing potential applied thereto.

Another object of this invention is the provision of einzel lens structures having electrical symmetry about the horizontal and vertical mid-plane thereof for focusing hollow curved electron beams.

A further object of this invention is the provision of a physically non-symmetrical einzel lens which eliminates the static electrical dissymmetries and space charge effects of heretofore employed physically symmetrical einzel lenses useful in focusing hollow curved electron beams.

A feature of this invention is an einzel lens structure including three electrodes positioned in tandem along the path of a hollow curved electron beam, each of said electrodes including inner and outer parts with respect to the electron beam path for passage of the hollow electron beam therebetween. The inner and outer electrode parts of the first and third electrodes are positioned to be physically symmetrical with the mean circumference of the hollow electron beam and the electrode parts of the second or central electrode are positioned to be physically

non-symmetrical with respect to the mean circumference of the hollow electron beam.

Another feature of this invention is an einzel lens structure including as the central electrode thereof concentric inner and outer cylinders whose circumferences adjacent the appropriate surfaces of the electron beam are related to the mean circumference of the hollow beam passing therebetween such that the space defined by the concentric cylinders is dissymmetrical to the mean circumference of the electron beam.

Still another feature of this invention is an einzel lens system for focusing hollow annular electron beams along a given path including annular electrodes having inner and outer parts disposed with respect to the beam path for passage of the beam therebetween, the electrode parts of certain ones of said electrodes having radii which according to a first order theory are related to the mean radius of the annular beam by the square root of the product of the outer radius of the inner electrode part and inner radius of the outer electrode part.

The above-mentioned and other features and objects of this invention will become more apparent by reference to the following description taken in conjunction with the accompanying drawings, in which:

Fig. 1 is a diagrammatic illustration of an electron gun system employing a physically symmetrical einzel lens structure of the prior art and the non-symmetrical equipotential configuration thereof;

Fig. 2 is a diagrammatic illustration of an electron gun system employing an einzel lens structure of this invention and the resulting symmetrical equipotential configuration thereof;

Fig. 3 is a diagrammatic illustration of a lens structure in accordance with this invention corrected for non-uniform space charge effects of annular drift tube regions; and

Fig. 4 is a diagrammatic illustration of an electron gun system employing an einzel lens structure corrected for both static and space charge effects in accordance with this invention.

Referring to Fig. 1, there is illustrated therein an electron gun system including an electron lens structure of the unipotential type indicative of the prior art arrangements for focusing curved electron beams. The gun system comprises a cathode 1 suitable for electron emission to form a hollow curved electron beam, a grid 2 cooperating in projecting the hollow electron beam along a given path and a unipotential lens system 3 disposed physically symmetrical to the mean circumference of the electron beam path.

While numerous curved electron beams may be emitted from cathode structures the most frequently used curved electron beam is a hollow cylindrical one. The description of the lens structures herein will be related to hollow cylindrical annular electron beams, but it will be obvious as the description continues that the corrections applied to the physically symmetrical lens system for hollow cylindrical annular electron beams may be applied in a similar manner to those lens systems employed in focusing curved electron beams other than hollow cylindrical ones, such as a hollow elliptical lens system and others having similar variations in curvature.

Electron devices suitable for producing curved electron beams may have electrodes both internally and externally to the beam. In some instances the internal and external electrodes will be at the same potential and in other instances will be at a difference of potential. At any rate, for proper action of the electrodes incorporated in the lens system, it is necessary to consider the forces acting on the curved hollow electron beam both at its outer and inner radii. It is desirable for proper focusing action that the radial electric fields from the main radius of the electron beam to its inner and outer extremities be symmetrical. Only when this condition is satisfied

will focusing be possible without deflection, or will deflection be possible without defocusing.

Turning again to Fig. 1, the lens system 3 is illustrated as being a physically symmetrical annular electrode structure including accelerating electrodes 4 and 5 and a focusing electrode 6 disposed symmetrically between electrodes 4 and 5. Each of the electrodes 4 and 5 include therein an annular aperture 7 for passage of the annular electron beam therethrough. Aperture 7 of electrode 4 is defined by an outer annulus 8 and an inner disc 9, each having a proper diameter to position aperture 7 symmetrically with respect to the mean circumference of the annular electron beam. The aperture 7 of electrode 5 is defined in a like manner and it will be obvious from the illustration that electrodes 4 and 5 are identical in all respects and disposed symmetrically from electrode 6. In the physically symmetrical electron lens, focusing electrode 6 likewise provides therein an aperture 10 for passage of the electron beam symmetrically therethrough with the confining walls of aperture 10 being defined by annulus 11 and disc 12. It will be recognized that in such a physically symmetrical lens structure the mean radius of the electron beam which passes symmetrically through apertures 7 and 10 is related to the radius of disc 12 and the inner radius of annulus 11. The relationship deducible from the geometry of the structure utilized in the prior art is

$$r_2 = \frac{(r_3 + r_1)}{2}$$

(employing the notations of Fig. 1) where r_1 equals the radius of annulus 12, r_2 equals the mean radius of the electron beam and r_3 equals the inner radius of annulus 11 of focusing electrode 6.

It has been found by investigation of the lens structure with the aid of an electrolytic tank measurement that the physically symmetrical electrode structures disclosed in the prior art have inherent static dissymmetries such that the electric fields from the mean radius of the electron beam to its inner and outer extremities are not symmetrical. This condition produces a radial deflection of the electron beam in addition to a focusing thereof. This radial deflection is illustrated by the equipotential plots shown in Fig. 1. It will be recognized that the greatest dissymmetry exists in the region of the saddle points 13. In fact, the saddle points 13 are displaced radially from the mean radius 14 of the electron beam. It has been further discovered that if the inner and outer electrode parts 11 and 12 were extended longitudinally to form concentric cylinders that the dissymmetries of the electric field are further complicated by an appreciable space charge built up between the cylinders.

Referring now to Fig. 2 and employing the same reference characters therein with respect to identical structure, an embodiment of the unipotential lens system of this invention is illustrated which overcomes the electrical dissymmetries of the prior art lens structure of Fig. 1. A lens system in accordance with this invention may include electrodes 4 and 5 identical with the electrodes 4 and 5 of Fig. 1 with apertures 7 being disposed symmetrically about the mean circumference or radius 14 of the electron beam. The correction applied to the lens structure of this invention is concerned with the modification of the focusing electrode 6a in a manner to position the aperture 10a to be physically non-symmetrical with respect to the mean radius 14 of the electron beam path. It has been discovered that this non-symmetrical positioning of aperture 10a shifts the saddle points 13 of the equipotential distribution for coincidence with the mean radius of the electron beam path. Tests performed on the lens system modified to have a physically non-symmetrical focusing electrode illustrated that good focusing of an annular electron beam was accomplished without radial deflection thereof.

The physically non-symmetrical characteristic of electrode 6a, as established by the inner radius of outer part 11a and the outer radius of inner part 12a, may be accomplished in either one of two ways. The first way would be to increase the diameter of disc 12 such that the radius r_1' of disc 12a is greater than the radius r_1 of disc 12 of Fig. 1. This would require a remachining of the inner electrode part of focusing electrode 6 and probably would be the most undesirable means of accomplishing the modification of a normal physically symmetrical unipotential lens structure. The preferred means of accomplishing the desired modification of electrode 6 would be to remove a predetermined amount of material by a machining process from the annulus 11, thereby making the radius r_3' of annulus 11a larger than the radius r_3 of annulus 11 of Fig. 1.

The modification of a physically symmetrical lens herein set forth is not restricted to the correction of static dissymmetries of physically symmetrical three-apertured lenses but may be employed to correct similar electrical dissymmetries in single-apertured or double-apertured lenses as well as other curved einzel lens systems.

While the lens systems of Figs. 1 and 2 are illustrated diagrammatically, attention is directed to the copending application of J. H. Bryant and A. G. Peifer, Serial No. 301,590, now Patent No. 2,753,484, entitled "Signal Indicating Device" for an example of the proposed structure and supporting means of the present lens structure to provide a cooperating mechanical assembly. Briefly the electrodes are held in a parallel relationship by an arrangement of ceramic tie rods, certain ones of which support the outer electrode parts and others of which support the inner electrode parts with the tie rods looped and secured together to form a rigid mechanical structure.

Having now illustrated the means of correcting an annular electrode structure for non-uniform static effects, it is necessary to consider the changes or dissymmetries produced by the presence of an electron beam in the structure. A general analysis is difficult but a few of the effects of space charge in an electrode structure may be resolved in an approximate manner. Any electron beam which is appreciably dense, if allowed to drift, will acquire in time a non-uniform cross-sectional charge and potential distribution due to the natural repulsion of the electrons in the electron beam. Therefore, within a drifting electron beam, there is some line or surface which is at a lower potential than the surrounding drift tube or region. Hence, an electrostatic field will exist between the potential minimum and the walls of the drift tube.

Fig. 3 illustrates a lens structure in accordance to this invention including therein as the central element, concentric cylinders operated at the same potential which define a drift region for the electron beam being focused by a lens structure of this type. The inner cylinder 15 may be considered to be a longitudinal extension of disc 12 of the focusing electrode 6 of Fig. 1, while the outer cylinder 16 may be considered a longitudinal extension of annulus 11 of focusing electrode 6. Electrodes 4 and 5 as before are appropriately positioned symmetrically with respect to electrode 6c. The electron beam passing through electrode 6c in the passage provided between the outer surface of cylinder 15 and the inner surface of cylinder 16 exhibits a certain radial electric field, E_o and E_i . For a first approximation, the potential minimum surface in the electron beam may be assumed to be an equipotential cylinder of radius r_2'' . If we let r_1'' and r_3'' represent the radii of the inner and outer drift tube walls, respectively, and assuming infinitely longer cylinders, it can be shown that $r_2'' = \sqrt{r_1'' r_3''}$ in order to have equal forces between the electron beam potential minimum and the respective drift tube walls.

This relationship may be deduced as follows. Starting

5 with the fundamental electric field relationship within a concentric cylinder arrangement, it may be shown that

$$E_o = \frac{V_B - V}{r_2'' 1 n_e r_3''}$$

and

$$E_i = \frac{V_B - V}{r_2'' 1 n_e r_1''}$$

10 where E_o equals the electric field from the potential minimum surface toward the outer electrode part, E_i equals the electric field from the potential minimum surface toward the inner electrode part, V_B equals the electron beam potential, V equals the electrode potential and r_2'' , r_1'' , and r_3'' are as defined above.

15 To have equal forces from the beam potential minimum toward the respective drift tube walls, E_o must equal E_i . Therefore,

$$\frac{V_B - V}{r_2'' 1 n_e r_3''} = \frac{V_B - V}{r_2'' 1 n_e r_1''}$$

20 and

$$1 n_e \frac{r_3''}{r_2''} = 1 n_e \frac{r_2''}{r_1''}$$

25 or

$$\frac{r_3''}{r_2''} = \frac{r_2''}{r_1''}$$

which results in $r_2'' = \sqrt{r_1'' r_3''}$.

30 Upon examining the above equations, it can be concluded that the diameter of either the inner or the outer cylinder may be adjusted to make $E_o = E_i$. Naturally, it would be best to decrease the large field, E_o , by decreasing r_3'' . In certain applications where the enclosure for the electron lens system is restricted in diameter, the increasing of r_3'' would be impractical and therefore, the radius of r_1'' should be increased.

35 Since proper focusing in a lens structure having a drift region requires equal forces between the electron beam potential minimum and the respective drift tube walls and the relationship $r_2'' = \sqrt{r_1'' r_3''}$ must be satisfied, it is obvious that the physically symmetrical system will not satisfy these conditions since in a physically symmetrical system

$$r_2'' = \frac{(r_3'' + r_1'')}{2}$$

40 By modifying a drift tube portion of such a unipotential lens structure in accordance with the formula

$$r_2'' = \sqrt{r_1'' r_3''}$$

45 there has resulted an equal current interception by the inner and outer walls and a much improved focusing of annular electron beams. A successful reduction to practice of a lens structure for a navigational aid application incorporating the modification herein described resulted in a lens where $r_3'' = 1.00$ inch, $r_2'' = 0.750$ inch, and $r_1'' = 0.5625$ inch.

50 Comparing the modification of electrode 6a of Fig. 2 with the necessary modification of the drift tube electrode 6b of Fig. 3, it will be recognized that both modifications are in the same direction. That is to say, r_3'' and r_1'' must be both increased or r_1'' and r_3'' must be both increased to remove the undesired electrical dissymmetries occurring in physically symmetrical lens systems. Recognizing this fact and the fact that the same relationship of radius changes holds for the removal of both static and space charge non-uniformities of electrical properties, lens structures of the unipotential type may be modified in accordance with the square root relationship set forth

herein to provide electrical symmetry for these lenses having both static and space charge nonuniformities. With reference to Fig. 4, an annular unipotential lens structure is illustrated which has been corrected for both static dissymmetry and nonuniform space charge effects.

Annular lens structure 3b is shown diagrammatically to comprise a first set of concentric electrodes 17 and 18 operated at one potential V_1 and a second set of concentric electrodes 19 and 20 operated at a second potential V_2 . The outer radius r_1''' of electrode 17 and the inner radius r_3''' of electrode 18 are related to r_2''' , the mean radius of the electron beam, by the square root of the product of r_3''' and r_1''' which will correct for the space charge effects present in the drift region between electrodes 17 and 18. The outer radius r_1'''' of electrode 19 and the inner radius r_3'''' of electrode 20 are related to r_2''' also by the square root of the product of r_3'''' and r_1'''' which will correct for the space charge effects present in the drift region between electrodes 19 and 20. It will be recognized, however, that r_1'''' is less than r_1''' and that r_3'''' is greater than r_3''' by an amount sufficient for a given application to assure that static dissymmetries do not exist between the first and second set of electrodes forming the lens structure 3b. This relationship of radii will remove space charge effects in each of the drift regions and will assure an equipotential plot of the electric field between the sets of electrodes which is electrically symmetrical about the mean radius r_2''' of the electron beam path.

Practically all electrode systems which have apertures therein to cooperate in focusing curved electron beams display non-uniform static equipotential distributions which result in non-uniform radial effects on electrons placed in geometrical planes of symmetry. In addition, space-charge effects result in unequal attraction of electrons to the inner and outer walls of an appreciably long drift region. The modifications or correction disclosed hereinabove have been related to hollow cylindrical type lens structure, but it must be kept in mind that these modifications can be effectively applied to electron lens structures other than cylindrical to remove the inherent electrical dissymmetries present therein in a manner similar to that disclosed herein for cylindrical type structures.

While I have described above the principles of my invention in connection with specific apparatus, it is to be clearly understood that this description is made only by way of example and not as a limitation to the scope of my invention as set forth in the objects thereof and in the accompanying claims.

I claim:

1. An electron gun structure using an electron lens of the einzel type to maintain the dimensions of a hollow curved electron beam substantially constant comprising means to project a hollow curved electron beam having a predetermined mean circumference along a given path, a plurality of electrodes disposed along said given beam path, means to couple a first potential to certain of said electrodes and a second potential to others of said electrodes to establish an electrostatic field between adjacent ones of said electrodes, each of said electrodes having unipotential inner and outer parts with respect to said hollow beam for passage of said hollow beam along said given path between said parts, said electrode parts of at least one of said electrodes being positioned in an asymmetrical relationship with respect to said predetermined mean circumference to establish a symmetrical electrostatic field about said mean circumference.

2. An electron gun structure using an electron lens of the einzel type to maintain the dimensions of a hollow curved electron beam substantially constant comprising means to project a hollow curved electron beam having a predetermined mean circumference along a given path, a plurality of electrodes disposed along said given beam path, means to couple a first potential to certain of said electrodes and a second potential to others of said elec-

trodes to establish an electrostatic field between adjacent ones of said electrodes, each of said electrodes having inner and outer parts with respect to said hollow beam for passage of said hollow beam along said given path between said parts, said electrode parts of at least one of said electrodes being positioned in an asymmetrical relationship with respect to said predetermined mean circumference to establish a symmetrical electrostatic field about said mean circumference, said inner part of said one of said electrodes having a given outer circumference and said outer part of said one of said given electrodes having a given inner circumference, the product of said inner and outer circumferences being related to the square of the mean circumference of said beam path.

3. An electron gun structure using an electron lens of the einzel type to maintain the dimensions of a hollow curved electron beam substantially constant comprising means to project a hollow curved electron beam having a predetermined mean circumference along a given path, a plurality of electrodes disposed along said given beam path, means to couple a first potential to certain of said electrodes and a second potential to others of said electrodes to establish an electrostatic field between adjacent ones of said electrodes, each of said electrodes having inner and outer parts with respect to said hollow beam for passage of said hollow beam along said given path between said parts, said electrode parts of at least one of said electrodes being positioned in an asymmetrical relationship with respect to said predetermined mean circumference to establish a symmetrical electrostatic field about said mean circumference, said electrodes being three in number and said one of said electrodes being disposed symmetrically between the other two of said electrodes, said one of said electrodes including said inner part having a given outer circumference and said outer part having a given inner circumference, the product of said given inner and outer circumferences being related to the square of the mean circumference of said given beam path.

4. An electron gun structure using an electron lens of the einzel type to maintain the dimensions of a hollow curved electron beam substantially constant comprising means to project a hollow curved electron beam having a predetermined mean circumference along a given path,

45 a plurality of electrodes disposed along said given beam path, means to couple a first potential to certain of said electrodes and a second potential to others of said electrodes to establish an electrostatic field between adjacent ones of said electrodes, each of said electrodes having inner and outer parts with respect to said hollow beam for passage of said hollow beam along said given path between said parts, said electrode parts of at least one of said electrodes being positioned in an asymmetrical relationship with respect to said predetermined mean circumference to establish a symmetrical electrostatic field about said mean circumference, said inner part including a disc and said outer part including an annulus disposed concentric to said disc.

5. A structure according to claim 4, wherein said disc and said annulus of said one of said electrodes have given outer and inner radii, respectively, and the mean radius of said beam path is related to the square root of the product of said given outer and inner radii.

6. An electron gun structure using an electron lens of the einzel type to maintain the dimensions of a hollow curved electron beam substantially constant comprising means to project a hollow curved electron beam having a predetermined mean circumference along a given path, a plurality of electrodes disposed along said given beam path, means to couple a first potential to certain of said electrodes and a second potential to others of said electrodes to establish an electrostatic field between adjacent ones of said electrodes, each of said electrodes having inner and outer parts with respect to said hollow beam for passage of said hollow beam along said given path

between said parts, said electrode parts of at least one of said electrodes being positioned in an asymmetrical relationship with respect to said predetermined mean circumference to establish a symmetrical electrostatic field about said mean circumference, said electrodes numbering three and being disposed transversely of said given beam path, each of said electrodes including a disc disposed within said given beam path and an annulus disposed to surround said given beam path, the product of the inner radius of said annulus and the outer radius of said disc of said one of said electrodes being related to the square of the mean radius of said given beam path.

7. A structure according to claim 6, wherein said one of said electrodes is disposed symmetrically between the other two of said electrodes.

8. An electron gun structure using an electron lens of the einzel type to maintain the dimensions of a hollow curved electron beam substantially constant comprising means to project a hollow curved electron beam having a predetermined mean circumference along a given path, a plurality of electrodes disposed along said given beam path, means to couple a first potential to certain of said electrodes and a second potential to others of said electrodes to establish an electrostatic field between adjacent ones of said electrodes, each of said electrodes having inner and outer parts with respect to said hollow beam for passage of said hollow beam along said given path between said parts, said electrode parts of at least one of said electrodes being positioned in an asymmetrical relationship with respect to said predetermined mean circumference to establish a symmetrical electrostatic field about said mean circumference, said one of said electrodes comprising a first cylinder disposed within said given beam path and a second cylinder disposed to surround said beam path, the inner radius of said second cylinder and the outer radius of said first cylinder being non-symmetrically related to the mean radius of said given beam path.

9. A structure according to claim 8, wherein the product of said inner and outer radii is equal to the square of the mean radius of said given beam path.

10. An electron gun structure using an electron lens of the einzel type to maintain the dimensions of a hollow curved electron beam substantially constant comprising means to project a hollow curved electron beam having a predetermined mean circumference along a given path, a plurality of electrodes disposed along said given beam path, means to couple a first potential to certain of said electrodes and a second potential to others of said electrodes to establish an electrostatic field between adjacent ones of said electrodes, each of said electrodes having inner and outer parts with respect to said hollow beam for passage of said hollow beam along said given path between said parts, said electrode parts of at least one of said electrodes being positioned in an asymmetrical relationship with respect to said predetermined mean circumference to establish a symmetrical electrostatic field about said mean circumference, said electrodes numbering at least two, each of said electrodes including a first cylinder disposed within said given beam path and a second cylinder disposed to surround said given beam path, said first cylinder having a given outer radius and said second cylinder having a given inner radius, the product of said given inner and outer radii being equal to the square of the mean radius of said given beam path.
- 20 11. A structure according to claim 10, wherein the outer radius of said first cylinder of one electrode is greater than the outer radius of said first cylinder of the other electrode by a given amount and the inner radius of said second cylinder of said one electrode is less than the inner radius of said second cylinder of said other electrode by a given amount to provide a symmetrical electrostatic field between said electrodes for focusing said beam without deflection thereof.
